UNITED STATES PATENT OFFICE.

WILLIAM B. BURK AND GEORGE W. BURK, OF PHILADELPHIA, PA.

DESIGN FOR A SPONGE-BASKET.

SPECIFICATION forming part of Design No. 13,139, dated August 8, 1882.

Application filed June 23, 1882. Term of patent 3½ years.

To all whom it may concern:

Be it known that we, WILLIAM B. BURK and GEORGE W. BURK, citizens of the United States, residing at Philadelphia, in the county of Philadelphia and State of Pennsylvania, have invented and produced a new and original Design for Sponge-Baskets; and we do declare the following to be a full, clear, and exact description of the invention, such as will enable others skilled in the art to which it appertains to make and use the same, reference being had to the accompanying drawing, and to the letters and figures of reference marked thereon, which form a part of this specification.

15 In the drawing is shown a perspective elevation of the improved sponge-basket.

a is the basket, which is made of wire woven in lattice-work into a frame having the form of a truncated pyramid, after the similitude of 20 the Egyptian obelisk. On the top of this lattice-work frame there is placed a wire scroll-work, a', which represents to the eye a capital or finished top of the pyramidal-shaped frame. b, b', b², and b³ represent cross or horizontal partitions, arranged within the lattice frame a, and by which the latter is divided into different compartments, c c' c², for the reception of different sizes of sponges.

25 d d' d² represent semicircular openings, in which are placed semicircular lattice-work doors d³ d⁴ d⁵, swinging into and closing the said opening.

The leading features of this design consist in its form, which represents the recently-imported Egyptian obelisk, and the lattice-work of which the frame is made, whereby when it is filled with sponges there is imparted to the

eye much the same effect that is imparted by the multifarious carvings which appear on the said obelisk.

40 Another feature of this design is the outline given by the finished top or capital; and a still further feature is the effect imparted by the different compartments, conveying to the eye the effect of a storied pyramidal-shaped 45 structure, having entrances into each compartment or story.

Having thus described our invention, what we claim, and desire to secure by Letters Patent, is—

50 1. The design for a sponge-basket herein shown and described, consisting of the pyramidal-shaped wire lattice-work frame made after the similitude of the Egyptian obelisk.

2. The design for a sponge-basket herein shown and described, consisting of the wire lattice-work frame made in the form of the Egyptian obelisk, and provided on its top with the open wire scroll-work.

3. The design for a sponge-basket herein shown and described, the same consisting of the wire lattice-work frame made in the form of the Egyptian obelisk, the open wire scroll-work on the top of the lattice-frame, the open or wire work partitions, and the semicircular 65 outlines on the side thereof.

In testimony whereof we affix our signatures in presence of two witnesses.

WILLIAM B. BURK.
GEORGE W. BURK.
